MILL ROLL STAND

Herbert C. Behrens, Haddon Heights, N. J., assignor to Samuel M. Langston Co., Camden, N. J., a corporation of New Jersey

Application June 7, 1943, Serial No. 490,001

10 Claims. (Cl. 242—58)

1

The present invention relates to roll stands of a type adapted for lifting heavy rolls of sheet material from a conveyor, carriage or other supporting means and supporting them in rotatable position so that the rolls may be unwound and a continuous running web supplied therefrom to any common type of mechanism for operating on the web, as for instance a corrugating, trimming, slitting, scoring or rewinding machine.

One object of the present invention is to provide a roll stand having new and improved means for centering its roll supporting members with respect to the roll to be lifted and supported, and for moving the supported roll into desired operative position with respect to the web pulling mechanism.

Another object is to provide a roll stand designed to operatively mount two rolls in proximity to each other and in such a manner as to effect the utmost economy of space. One of these rolls may, for example, serve as a reserve roll while the other is being unwound.

According to the invention, parallel angularly movable roll supporting members or arms carry respective chuck spindles adapted to extend into and hold the ends of the tubular core of the roll to be raised.

As a feature of the present invention, means are provided for simultaneously moving both roll supporting arms towards or away from each other to accommodate rolls of different widths.

As a further feature, means are provided for moving the pair of roll supporting arms laterally in unison in either direction substantially parallel to the roll axis to center accurately said arms with respect to the roll to be lifted and supported, and to center the supported roll in correct operative position with respect to the machine which operates on the delivered web.

As another feature, new and improved means are provided for adjusting one end of the supported roll transversely relative to the axis of the roll, to compensate for differences in the diameters of the supported roll and thereby eliminate slackness on one side of the web.

As a further feature, a two speed drive is provided for lifting and lowering the roll supporting arms, whereby the high speed drive may be used to raise or lower the arms without load and the low speed may be employed when raising or lowering a heavy roll.

As another feature, the two roll supporting arms carry brakes for both ends of the supported roll to control the tension of the web being pulled from said roll.

2

As a further feature, new and improved chuck spindles are provided at the ends of the roll supporting arms for supportably engaging the ends of the roll.

Various other objects, features and advantages of the invention will be apparent from the following particular description, and from an inspection of the accompanying drawings, in which

Fig. 1 is an end view of one form of roll stand embodying the present invention, and shown in roll supporting position;

Fig. 2 is a section taken approximately on line 2—2 of Fig. 1, one of the rolls being removed;

Fig. 3 is a section taken approximately along the line 3—3 of Fig. 2;

Fig. 4 is an end view of another form of roll stand embodying the present invention, and shown in roll supporting position;

Fig. 5 is a section taken approximately along the line 5—5 of Fig. 4, one of the rolls being omitted;

Fig. 6 is a section taken along line 6—6 of Fig. 4;

Fig. 7 is a section taken along line 7—7 of Fig. 5;

Fig. 8 is a fragmentary horizontal section of another form of roll stand embodying the present invention, and shown employing hydraulic motive power for operating the various adjustable elements; and

Fig. 9 is an end view of the roll stand of Fig. 8, taken approximately along the line 9—9.

Referring to Figs. 1—3 of the drawings, the roll stand is fixed on a floor 10 between two roll trans-

porting means shown as conveyor rollers 11 supported in channels 12 in said floor. The rolls A and B to be lifted and supported by the roll stand are moved along the conveyor rollers 11 until they reach approximately the correct positions on opposite sides of said stand. The stand is then operated to move its roll supporting members into engagement with said rolls, and to elevate said members and the rolls into proper position with respect to the corrugating, slitting,

scoring, rewinding or other similar machine which receives and operates on the web. The two rolls A and B may serve simultaneously as the running rolls of two of these operating machines on opposite sides of the roll stand, but ordinarily only one of these rolls serves as a running roll for a machine, while the other is held in reserve for delivery to said machine when the first roll has been used up.

The roll stand comprises a pair of end frames 13 and 14 between the conveyors 11 and spaced

to a distance greater than the maximum length of the rolls to be supported. Extending between these frames 13 and 14 are two horizontally spaced rock shafts 15 disposed one above the other. One of the shafts 15 carries a pair of roll supporting arms 17 extending outwardly to the left of the roll stand as viewed in Fig. 1 to engage the roll A, and the other shaft 15 carries a pair of roll supporting arms 17 extending outwardly to the right of the roll stand to engage the roll B.

Each of the rock shafts 15 is supported at one end on the frame upright 14 in a manner to permit limited endwise adjusting movement of said shaft, and for that purpose has an end portion 25 of reduced diameter supported on bearing rollers 26 journalled in said upright and provided with circularly grooved shaft engaging peripheries as shown particularly in Fig. 3. The other end of each shaft 15 is supported by bearing rollers 27 which may be similar to the bearing rollers 26, and which are journalled in a frame 28 on the upright 13. The two frames 28 are superposed and are slidably adjustable in respective openings 30 in the upright 13 to tilt either rock shaft 15 for the purpose to be made apparent.

The roll supporting arms 17 are splined to their corresponding shafts 15 to cause angular movement of said arms upon rotation of said shafts and to permit movement of said arms along their corresponding shafts for the purpose to be made apparent. For rotating each of the shafts 15, there is provided a two-speed gear train which is shown manually operated from a hand wheel 35 fixed to a shaft 36 journalled in a corresponding frame 28, but which, if desired, can be operated from a motor in place of said hand wheel. The slow speed drive to each shaft 15 desirably comprises a worm 37 on the hand wheel shaft 36 housed in the corresponding frame 28 and meshing with a worm wheel 38 journalled in said frame. This worm wheel 38 is on a shaft carrying a worm 41 meshing with a worm wheel 42 which is housed in the frame 28 and which embraces the corresponding shaft 15 with a rotative fit. This worm wheel 42 can be disengageably coupled to the shaft 15 in a manner to be described.

The high speed transmission between the hand wheel 35 and the shaft 15 desirably comprises a spur pinion gear 50 on the hand wheel shaft 36 driving through an intermediate gear 49 a spur gear 51 housed in the frame 28 and embracing the shaft 15 with a rotative fit.

For coupling the shaft 15 selectively to either the slow or high speed drive, the end of the shaft 15 is hollowed to receive a clutch lever 52 pivoted at its inner end 53 to said shaft, and formed with a handle 54 at its other end projecting outwardly beyond said shaft to render said handle easily accessible for manipulation. A dog 55 pivotally connected to lever 52 extends through an opening in the shaft 15 and is adapted to be moved by angular movement of the lever 52 into or out of coupling drive engagement with the gear 42. A dog 56 pivotally connected to the lever 52 extends through an opening in the shaft 15 and is movable into or out of coupling engagement with the gear 51. The dogs 55 and 56 are diametrically arranged on the clutch lever 52 so that when one of said dogs is in gear coupling engagement, the other is out of gear coupling engagement. A latch 58 hinged at 57 to the frame plate 59 locks the clutch lever 52 in either one of its two operative positions, and is movable about its hinge connection to permit the angular movement of said clutch lever.

In the operation of the roll stand so far described, when it is desired to prepare the two pairs of supporting arms 17 in position to receive the rolls A and B, each of the clutch levers 52 is moved in position to couple the spur gear 51 of the high speed gear train to the shaft 15, and the hand wheel 35 is rotated to drive the shaft 15 through said gear train to raise angularly the corresponding roll supporting arms 17 in an elevated position in which they will not interfere with the movement of the rolls A and B alongside of the roll stand. These rolls A and B are then pushed over their respective conveyors until they lie midway between the corresponding arms 17. Each of the hand wheels 35 is then turned in a direction to lower the corresponding pair of arms 17 at comparatively high speed to a position in which they flank the ends of the hollow center cores 57' of the corresponding paper roll. The two arms 17 are then moved towards each other into supporting engagement with the roll core 57' in a manner to be described, the clutch lever 52 reversed so that the worm wheel 42 of the low speed drive is coupled to the shaft 15, and the hand wheel 35 rotated to angularly elevate the loaded arms 17 at a slow speed but with high mechanical advantage, and thereby raise the paper roll to the desired elevated operative position with respect to the paper pulling machine.

For supportably engaging the paper rolls, each of the arms 17 desirably carries at its outer end a roller bearing 60 in which is journalled a spindle 61 held against axial movement with respect to said arm. The spindle 61 carries at its inner end an expansible chuck 62, comprising a head 63 forming an extension of said spindle of reduced diameter for insertion into the roll core 57', and having a series of slots in which are pivotally connected respective cleats 65. The extent of inward axial movement of the spindles 61 with respect to the paper roll A is limited by the engagement of a shoulder 66 on the spindle 61 with the end of the roll.

To expand the cleats 65 into firm drive engagement with the roll core walls, there is provided a shaft 67 threaded in the spindle 61, and having a rotary handle 68 at its outer end and a cam cone 70 near its inner end. As the handle 68 is turned, the cam cone 70 is moved axially to thrust the cleats 65 radially outwardly into driving engagement with the roll core wall.

For moving the opposed arms 17 of each co-operating pair towards or away from each other, there is provided a screw 75 which is supported in suitable bearings 76 attached to the corresponding shaft 15 for revolution therewith, and which extends along one side of said shaft substantially parallel thereto. This screw 75 has left and right hand thread engagement with the two opposed arms 17 so that as this screw is turned, these arms are moved towards or away from each other according to the direction of rotation of said screw.

For rotating the screws 75, there is provided a motor 80 supported on the frame upright 14, a pinion 81 on the motor shaft, and a gear transmission between said pinion and each of the screws 75. The upper transmission comprises a spur gear 82 meshing with the pinion 81 and driving a spur gear 83 through an intermediate pinion 84 journalled on the same center as shaft 15. The gear 83 has its shaft connected to the screw 75 through a universal coupling 85 shown in the form of a knuckle joint to permit tilting 75 of the screw 75 with its associated shaft 15 for

the purpose to be made apparent. The lower transmission is similar to the upper transmission except that an intermediate gear 83 is provided between the lower gears 82 and 84 driving the lower screw 75 through lower gear 83.

The screw 75 revolves about the axis of its associated shaft 15 when this shaft is rotated. To maintain drive connection to the screw 75 irrespective of its angular position with respect to the axis of the shaft, the spur gear 83 is journaled in a bearing 86 fastened to shaft 15 to give said bearing the same angular movement.

Each gear 82 is splined to its corresponding shaft 79 journaled in the frame upright 14, so that said gear is shiftable along said shaft. A throwout yoke 87 engages a collar or other element rigid with the gear 82 and is operated from a handle not shown to shift said gear in or out of mesh with the pinion 84 while maintaining mesh engagement with the drive gear 81. By means of this arrangement, either screw 75 or both screws 75 simultaneously may be operated to bring the corresponding pair of arms 17 in centered position with respect to their associated paper roll.

After arms 17 of each pair have been angularly moved into position so that their roll supporting spindles 61 are centered with respect to the corresponding roll cores 57', the motor 80 is energized to rotate the screw 75 and move said arms 17 towards each other. As these arms 17 are drawn towards each other, their chucks 62 move into the interior of the roll core 57' and come to rest when the spindle shoulders 66 engage the outer ends of the roll. The hand wheels 68 are then turned manually to cause the cams 70 to thrust the cleats 65 outwardly against the inside wall of the roll core 57', causing some indentation and preventing the paper roll from rotating about the chucks.

After the chucks 62 have been properly inserted in the core of the corresponding paper roll, the clutch lever 52 is shifted to couple the gear 42 to the shaft 15. The hand wheel 35 is then rotated to elevate the arms 17 through the low speed drive and suspend the roll in position for unwinding operations.

To square the roll in position to prevent slackness on one side of the web due, for instance, to differences in the diameter of the roll at its ends, each of the slide frames 28 is moved in the upright 13 by means of a screw 90 journaled in said upright and formed at its ends to receive a suitable turning tool. This screw 90 is threaded in the slide frame 28 and is held against axial movement, so that upon rotation thereof, said frame is adjustably moved in its respective frame opening 30 and the shaft 15 correspondingly tilted.

To move the arms 17 of each cooperating pair laterally in unison in the same direction for accurate centering of said arms with respect to the roll to be lifted, or accurate centering of the supported roll with respect to the paper pulling machine, each of the slide frames 28 has rotatably connected to one end thereof a hand wheel 91 having a radially inward flange connection to its respective shaft 15 and a threaded connection to the slide frame 28, whereby upon rotation of said hand wheel 91, the shaft 15 is moved axially a limited distance and the arms 17 carried by said shaft correspondingly moved.

Each of the arms 17 carries a brake device for controlling the tension on the web of the running roll. Each of these brake devices comprises a brake wheel or sleeve 95 keyed to the outer

end of the chuck spindle 61 for rotation therewith. A linkage is provided to actuate a pair of opposed brake shoes 96 and 97 in contact with the periphery of the brake sheave 95. This linkage is shown comprising links 98, 99, 100 and 101 pivotally carrying the brake shoes 96 and 97 respectively. The links 98, 99 and 100 are pivotally interconnected at 102 and 103. The fourth link 101 has a slot and pin connection at one end with the link 99 and is bifurcated at its other end to receive the link 100. This link 100 has threaded thereon a hand wheel 104 which bears against the bifurcated end of the link 101 to provide initial brake tension and which may be loosened to allow link 100 to move outwardly so as to be disengaged from the link 101, thereby rendering the brake inoperative.

The brake pressure of the shoes 96 and 97 on the brake sheave 95 may be controlled manually by the manipulation of the hand wheel 104 as described, or automatically by a web tensioning device, which may comprise a spring-pressed tension roller 105 and a pair of spring loaded idler rollers 106 and 107, the paper from the roll being threaded over and around these rollers 105, 106 and 107 as shown. The tension roller 105 is pivotally supported through brackets 108 and a rock shaft 110 on the frame of the roll stand to allow said tension roller 105 to move up or down according to the tension of the paper passing over it. Between the rock shaft 110 and the brake device is a linkage comprising links 111, 112 and 113. The link 113 carries at one end a cam 114 extending in a slot 115 at one end of the brake link 101. As the tension roller 105 moves up or down according to the tension of the running paper thereon, this movement is transmitted to the cam 114. The resulting rotation of this cam 114 causes the links 98 and 101 to move towards or away from each other and thereby causes the brake shoes 96 and 97 to move in and out with respect to the brake sheave 95. Therefore, when the running paper from the roll slack is sufficient to cause dropping of the tension roller 105, the brake shoes 96 and 97 are automatically moved inwardly towards the brake sheave 95 to increase the brake pressure, and vice versa.

In the form of the invention shown in Figs. 4 to 7, the rolls A and B are adapted to be transported to centered position with respect to the roll stand by means of a dolly system comprising a roll supporting carriage 120 movable along main tracks 121 until in position opposite the roll stand. In this position, the carriage 120 will move on to a truck 122 movable along tracks 123 extending transversely of and below the main tracks 121. By means of this transportation system, the rolls A and B can be moved towards or away from the roll stand transversely of the roll axes after they have reached a center position with respect thereto.

In the form of the invention shown in Figs. 4 to 7, the two arm carrying shafts 15a are supported at one end in the frame upright 14a and at the other end in slide frames 28a which are guided in respective openings 30a in the frame upright 13a, and which are adjusted therein through adjusting screws 90a to square the supported rolls. The two slide frames 28a are alongside of each other, so that the shafts 15a are at the same level. Each of these shafts 15a is rotated through a single speed from a hand wheel 35a or a motor substituted in place of said hand wheel. The drive transmission between

each hand wheel 35a to its corresponding shaft 15a comprises a worm 125 on the spindle of the hand wheel 35a meshing with a worm wheel 126 on a shaft 127 which also carries a worm 128 meshing with a worm wheel 130 keyed to the corresponding shaft 15a. A suitable latch may be provided for locking the shafts 15a to the frame uprights 13a and 14a when these shafts have been rotated in proper position.

The hand wheels 31 as in the construction of Figs. 1 to 3, serve to adjust the shafts 15a axially to move the arms 17a in unison in proper position with respect to the rolls A or B.

Each of the shafts 15a has a groove 135 extending lengthwise thereof to receive the screw 15a axially of said shaft. This screw 15a is supported in the shaft groove 135 in suitable bearings 13a mounted in said groove. With the screw 15a axially supported in its corresponding shaft 15a, no special provisions need be made to maintain a drive connection to said screw as said shaft is rotated.

The arms 17a embrace the outside of their corresponding shaft 15a, and have respective projections 136 which extend snugly into corresponding shaft grooves 135 and which are threaded on corresponding screws 15a. Each pair of cooperating arms 17a has a right and left hand threaded connection with a screw 15a, so that said arms are keyed to said shaft for rotation therewith, and slide therealong in opposite directions upon rotation of said screw.

The screws 15a are driven from the motor 80a by a drive gear 81a on the motor shaft and a transmission from said drive gear to each of said screws. Each of these transmissions includes a gear 82a meshing with the drive gear 81a, and with a driven gear 83a mounted on a shaft having a universal connection 85a to the screw 15a.

Either one of the screws 15a may be disconnected from the motor drive by means comprising a throw-out yoke 81a engaging a collar or other element rigid with the gear 82a, and having a rotatable connection with one end of a shaft 141 journalled in the frame upright 14a. The other end of this shaft 141 is threaded in the frame upright 13a and is secured to a hand wheel 142, so that upon rotation of said hand wheel, the shaft 141 is moved axially to shift the gear 82a into or out of mesh with the driven gear 83a while maintaining drive connection between the gears 81a and 82a.

The form of web tensioning device which is indicated in Figs. 4 and 5, comprises a spring loaded tension roller 145 journalled in slidable bearing blocks 146, each of which has a rack 147 driving an electric torque motor 148 through an intermediate pinion 150. This torque motor 148 in turn engages a pinion on a shaft 151, the rotational movement of which is transmitted to the link 98a of the brake device by links 152 and 153. The motor 148 is always energized, and as the tension roller 145 moves under the action of the spring and the tension of the paper, this roller movement stops the motor 148 or allows motor 148 to rotate, which in turn tightens or loosens the brake on the paper roll.

The brake device comprises the four links 98a, 99a, 100a and 101a arranged in the form of a rectangle around the brake sheave 95. The two links 98a and 101a have pin and slot connections with the link 99a, and said link 98a is pivoted at 154 to the corresponding arm 17a. As the link 98a is moved angularly about the pivot 154 in response to the movement of the tension roller 75

145, the brake shoes 96 and 97 pivotally carried by the opposed links 98a and 101a are moved in or out with respect to the brake sheave 95.

In Figs. 8 and 9 is shown the application of fluid power for actuating the various adjustable elements of the roll stand. For instance, to rotate the shaft 15b to move angularly the arms 17b, there is provided on one of the frame uprights 13b a hydraulic cylinder 160 having suitable inlet and outlet for the actuating fluid, and having a piston 161 connected to a rack 162 meshing with a gear 163 keyed to the end of the shaft 15b. By controlling the admission and discharge of the actuating fluid from the cylinder 160, the shaft 15b may be made to rotate into any suitable position.

By means of a hydraulic cylinder 165 fixed in the groove 135 of the shaft 15b, and by providing dual piston connections to the two arms 17b, these arms can be moved in unison towards or away from each other.

For moving the shaft axially to move the two arms 17b in unison in the same direction, a hydraulic cylinder 166 may be provided with a piston connection to the axial portion of said cylinder. This hydraulic cylinder 166, for instance, may be supported by brackets 167 to the frame upright 13b.

The chuck spindles 61b can also be hydraulically controlled by providing each of said spindles with a hydraulic cylinder 170 having a piston connection to the cleat expanding shaft 61b. The chuck itself instead of having three expandable cleats as shown in the constructions of Figs. 1 to 5, may have merely one expandable cleat 65 and a series of fixed radially outwardly projecting bosses 171.

The different hydraulic units can be controlled from a single station to effect the necessary roll stand operations. In all other respects, the roll stand of Figs. 8 and 9 may be similar to that of Figs. 1 to 7.

As many changes can be made in the above apparatus, and many apparently widely different embodiments of this invention can be made without departing from the scope of the claims, it is intended that all matter contained in the above description or shown in the accompanying drawings shall be interpreted as illustrative and not in a limiting sense.

What is claimed is:

1. A roll stand having a shaft, a pair of arms keyed thereto for rotatably supporting a roll of sheet material therebetween, a drive member, a low speed transmission for connecting said drive member to said shaft for rotating the latter and lift the roll, a high speed transmission for connecting said drive member and said shaft for rotating the latter and lower said roll, means for moving said arms in a direction parallel to the axis of said shaft, means for moving one end of said shaft laterally in respect to the other end to tilt the axis of said roll, and means controlled by the tension of the sheet withdrawn from said roll for varying the resistance to the rotation of said roll.

2. A roll stand including a shaft, a pair of opposed roll supporting members keyed thereto, a pair of gears on said shaft, a drive member, a high speed transmission between said drive member and one of said gears for rotating said shaft in one direction, a low speed transmission between said drive member and said gear for rotating said shaft in the opposite direction, and means for alternately connecting one of said

gears to the shaft and disconnecting the other therefrom.

3. A roll stand including a shaft, a pair of roll supporting members keyed thereto, a worm gear on said shaft, a spur gear on said shaft, a hand wheel, a transmission between said hand wheel and said worm gear, a transmission between said hand wheel and said spur gear, and means within said shaft for locking either the spur gear or the worm gear to said shaft.

4. A roll stand including a shaft having a pair of roll supporting arms keyed thereto and movable in vertical planes, a threaded rod coaxial with said shaft and having righthand and lefthand threaded portions engaging said arms respectively, a motor having a stationary base, and gearing connections between said motor and said rod.

5. A roll stand including a substantially horizontal shaft having a pair of roll supporting arms keyed thereto and movable in vertical planes, a threaded rod coaxial with said shaft and having righthand and lefthand threads engaging portions of the two arms carried by said shaft, a motor having a stationary base, gearing connections between said motor and said rod, and means for interrupting the transmission of power from said motor to said rod.

6. A roll stand including a shaft having a pair of roll supporting arms, separate bearing members for the opposite ends of said shaft, means associated with one of said bearing members for

rotating said shaft to raise or lower the roll, and means associated with one of said bearing members for bodily moving the corresponding end of said shaft and thereby changing the angle of the axis of the roll.

5 7. A roll stand including a shaft having a pair of radially extending roll supporting arms, a bearing member for one end of said shaft, and means for moving said member laterally to thereby tilt the axis of the roll.

10 8. A roll stand including a shaft having a pair of radially extending roll supporting arms, a bearing member for one end of said shaft, means for moving said member laterally to thereby tilt the axis of the roll, and means associated with said bearing member for rotating said shaft to raise or lower the roll.

15 9. A roll stand including a shaft, a pair of roll supporting members keyed on said shaft and extending radially therefrom, means for rotating said shaft to raise and lower the roll carrying portions of said members, and means for tilting said shaft to tilt the axis of the supported roll.

20 10. A roll stand including a shaft, arms keyed thereto and having roll supporting elements, means for moving said arms along said shaft and toward and from each other, means for rotating said shaft to move the arms in vertical planes, and means for moving one end of said shaft laterally in respect to the other end to tilt the 25 axis of the supported roll.

30 HERBERT C. BEHRENS.
